WALTER L. CONWELL, OF MONTCLAIR, NEW JERSEY, ASSIGNOR TO TRANSPORTATION UTILITIES COMPANY, OF NEW YORK, N. Y., A CORPORATION OF WEST VIRGINIA.

FRICITION DEVICE FOR HOLDING WINDOW-CURTAINS.

1,111,735.

Specification of Letters Patent. Patented Sept. 29, 1914.

Application filed January 9, 1912. Serial No. 670,234.

To all whom it may concern:

Be it known that I, WALTER L. CONWELL, a citizen of the United States, residing at Montclair, in the county of Essex and State 5 of New Jersey, have invented new and useful Improvements in Friction Devices for Holding Window-Curtains, of which the following is a full, clear, concise, and exact description, reference being had to the accompanying drawing, forming a part of this 10 specification.

My invention relates to a friction device for holding window curtains.

One of the objects of my invention is to 15 provide a device for holding a curtain in any desired position by means of friction acting in opposition to the action of a spring which tends to move said curtain.

Another object is to provide friction holding means which is effective to resist movement of the curtain in one direction but not in the opposite direction.

Another object is to provide means permitting a manual release of the friction 25 when desired.

A further object is to provide a friction device of simple and economical construction.

The invention may be embodied in various 30 forms. In the accompanying drawings I have illustrated two embodiments which I have worked out in practice and which have certain practical advantages. I do not limit myself, of course, to these two forms.

The views in the drawings are as follows:

Figure 1 is a side elevation partly in section of one form of friction device. Fig. 2 is an end elevation thereof. Fig. 3 is a plan 40 view of the blank from which the main body portion of the device is formed. Fig. 4 is a side elevation of another form of friction device.

Referring to the first form illustrated, a 45 rod is shown which is applied to the lower end of a window curtain or shade in the usual manner. The rod is made in two sections 1, 1 as is customary, the sections being adapted to be drawn toward each other by 50 means of the pinch handles 2, which are preferably arranged about the middle of

the lower edge of the curtain. The handles 2 are normally held apart by springs 3, but may be moved together against the action of said springs to permit a ready raising or 55 lowering of the curtain in the manner hereinafter described. Each end of one of the sections of rod 1 has secured thereto a shoe provided with a friction device. These shoes are made preferably in right and left 60 hand forms. Inasmuch as the two shoes and the parts associated therewith are substantially identical, I have illustrated and will describe only one of them from which the operation of the other will be clearly 65 apparent. The end of the section of rod 1 is suitably secured to a shoe, comprising side plates 4. Said rod may be secured thereto in any suitable manner, as, for example, by rivets. The two side plates, together with a 70 connecting strip or wall 5, are preferably integral, being stamped from a blank as shown in Fig. 3, and provide an inclosure within which the friction wheels 6 are located. These wheels are constructed of any 75 suitable material and are adapted to turn freely except when restrained by the small rollers 7 which are wedged or jammed between the peripheries of said wheels and the adjacent guides 8. These guides constitute in effect a continuation of the wall 5 and are struck up from the blank. Abutments 9, also preferably struck up from the metal of the blank, are provided to prevent 80 the rollers 7 from riding over on to the opposite side of the wheels.

Although the rollers 7 are illustrated as circular in outline, other configurations may, of course, be employed. For example, the rollers might be of polygonal outline, or 85 small cams might be employed.

The wheels 6 are adapted to run in the usual groove provided in the side of the window where this type of curtain is employed and said wheels bear against the bottom walls 10 of said groove. It will be apparent that the device as a whole may descend freely when the curtain is drawn down by hand, as during the descent the wheels as seen in Fig. 1, rotate clock-wise, 95 thereby tending to move the rollers 7 toward the stops 9. When the shoe is moved up 100

wardly, however, the rollers 7, which are normally in the position shown in Fig. 1, at once are wedged or jammed into the V-shaped end in the inclosure in which they are confined and act as a brake on the wheels. These rollers may be constructed of steel or other suitable material. The parts are preferably so designed that the rollers exert sufficient friction to prevent the rod sections 10, 1, 1 from being raised in response to the action of the usual torsional spring tending to hold the curtain, and hence the rod, in uppermost position. The friction between the wheels 6 and the stationary wall 10, however, is not so great but that the curtain rod may be forcibly moved upward by hand, if desired, without moving the handles 2 toward each other, the wheels slipping in the grooves. Of course, it is apparent that by 15 moving the handles toward each other the two sections of the rod and the various parts carried thereby, are moved toward each other, thereby releasing the friction between the wheels and the grooves. Of course, 20 when the handles 2 are pinched the curtain may be moved either up or down freely. In addition, the curtain may be readily pulled down without pinching the handles and the curtain may be forcibly raised, in spite of 25 the friction of the parts, without moving said handles toward each other. It will be further apparent that the curtain may be lowered to any desired position and left in that position.

35 In the form illustrated in Fig. 4, the wheels 6 are provided with small cams 10, which I have illustrated in the form of small rollers, eccentrically pivoted at 11 and bearing against the peripheries of said 40 wheels to resist rotation thereof in one direction but not in the other direction.

I do not desire to limit myself to the details described and illustrated, as I am aware that other forms may be devised which fall 45 within the scope of the invention as expressed in the appended claims.

I claim as my invention:—

1. In a curtain fixture, the combination of a curtain stick, a friction shoe carried 50 by each end of said stick, each friction shoe comprising a casing provided with curved ends, wheels pivoted to the walls of said casing eccentric with said curved ends, and rollers confined between the peripheries of 55 said wheels and said curved casing ends, whereby rotation of said wheels in one direction will be opposed by the wedging of said rollers between the peripheries of said wheels and the eccentric ends of said casing.

2. In a friction shoe, a guide wheel, an inclosing casing, said casing being provided with a wall approaching the periphery of 65 said wheel at an acute angle, and a roller confined in the space between said wall and

the periphery of said wheel, whereby as said wheel is rotated in one direction, said roller will crowd into said acute angle and exert a braking action on said wheel, and whereby as said wheel is rotated in the opposite direction, said roller will be moved toward the open end of said angle to release said wheel. 70

3. In a friction device for curtains, a supporting member, a wheel carried thereby 75 and freely rotatable, a guide also carried by said member and arranged adjacent the periphery of said wheel co-operating with said periphery to form a V-shaped inclosure, a roller located within said inclosure 80 and normally tending toward the narrow end of said inclosure, whereby rotation of said wheel in one direction tends to wedge said roller farther into said narrow end, whereby said roller exerts a braking effect 85 on said wheel.

4. A friction device for a curtain comprising, in combination, two plates suitably spaced apart, a plurality of wheels arranged between said plates and having their peripheries projecting beyond said plates, guide walls also arranged between said plates and adjacent each wheel, one guide wall and the periphery of each wheel co-operating to form a V-shaped recess, and 95 a roller located in each V-shaped recess and adapted to cause friction against the periphery of the corresponding wheel when said wheel is turning in the proper direction. 90

5. A friction shoe for curtain sticks, comprising an integral inclosing casing, rotatable disks provided with uninterrupted peripheries and smooth, flat sides, pivoted between the side walls of said casing, said 105 casing having end walls approaching the peripheries of said disks at acute angles, and friction rollers confined between the peripheries of said disks and said end walls to exert a braking action in one direction of rotation of said disks. 110

6. In a friction shoe, in combination, a plurality of guide wheels, an inclosure therefor, one wall of said inclosure approaching the periphery of one of said wheels whereby 115 a V-shaped recess is formed, and a friction device located in said V-shaped recess and adapted to exert a braking effect on said wheel during rotation in one direction but not in the other direction. 120

7. In a friction shoe, in combination, a plurality of guide wheels, an inclosure therefor, said inclosure comprising an integral sheet metal structure having one of its walls arranged approximately tangentially to one 125 of said wheels to form a recess for a friction device and a friction device movably mounted in said recess.

8. A friction shoe comprising an inclosing casing formed from a blank, said casing 130

having a pair of side walls, a connecting cross wall, and curved end walls, the extremity of said curved end walls terminating near the open side of said casing, and
5 guide wheels rotatably mounted in said side walls, the axis of said wheels being held in fixed relation to said side walls.

In witness whereof, I have hereunto subscribed my name in the presence of two witnesses.

WALTER L. CONWELL.
